UNITED STATES PATENT OFFICE.

NELSON GOODYEAR, OF NEW YORK, N. Y., ASSIGNOR TO MAINE DEVELOPMENT CORPORATION, A CORPORATION OF MAINE.

CARBURETER.

1,082,865.

Specification of Letters Patent. Patented Dec. 30, 1913.

Application filed January 30, 1909. Serial No. 475,278.

To all whom it may concern:

Be it known that I, NELSON GOODYEAR, a citizen of the United States, and a resident of the borough of Manhattan, city, county, and State of New York, have invented certain new and useful Improvements in Carbureters, of which the following is a specification, illustrated by drawings.

This invention relates to carbureters, more particularly those which are adapted to generate an inflammable gas from a volatile liquid to be used in connection with blow pipes.

In the accompanying drawings, Figure 1 is a longitudinal cross section through the body of the carbureter. Fig. 2 is a top or plan view.

Referring to Fig. 1, A is the body of the carbureter, cylindrical in form and preferably made of metal which is divided into two compartments B and C. The upper compartment B is preferably filled with an absorbent material such as felt or canton flannel, adapted to be soaked with any inflammable volatile liquid such as high grade gasolene or sulfuric ether.

Gas, for example compressed oxygen or air, enters on the side of the carbureter through the nipple or hose connection D and thence passes downwardly through the pipe E, which is coiled helically, finally entering the lower compartment C through the opening F. The compartment C forms a condensation or drip chamber. From the compartment C the gas passes upwardly through the opening G and the coil H which terminates at its upper end in the pipe I leading to a valve head J. From the valve head J a pipe K leads to the bottom of the upper compartment B of the carbureter. The access of gas to the pipe K is controlled by the needle valve L having a suitable thumb-screw M. The valve head J also connects with another needle valve N which is provided with a hose nipple O and is adapted to be controlled by the thumb-screw P. The upper compartment B of the carbureter is provided at its upper end with a cover R adapted to be screwed onto the top S. A gasket or washer of lead or other suitable material is preferably fastened between the cover R and the upper rim U of the top S. A screw-threaded outlet V is made in the center of the cover R, which is adapted to receive a hollow plug W on which is mount-

ed the outlet cock Q, which is provided with a hose nipple X. As the gas generated in such carbureter is very inflammable, it is desirable to have an explosion arrester between the outlet and the tube leading to the burner. This is conveniently provided by filling the hollow plug W with shot or disks cut from wire screens. In case shot are used the bottom of the cavity in the plug is closed with a disk of wire screen or perforated metal, as shown at Y. To prevent the absorbent material from swelling and closing the entrance to the outlet of the plug W I provide a cone Z of perforated metal or wire gauze, which is so located as to keep the absorbent material a short distance away from the outlet. The side of the upper compartment B is provided with a removable overflow plug a which serves to indicate when the carbureter is filled to the proper level. The lower compartment C is provided with a drain plug b by which condensation may be withdrawn from time to time.

Regarding the operation of the carbureter, it should be understood that it is intended to be used with compressed air, oxygen, or other gases which are supporters of combustion, and has for its function the saturation or carbureting of such gases with the volatile vapors of inflammable liquid so as to generate an inflammable gas. Carbureters of this type are preferably used in connection with oxygen gas, which may be drawn from cylinders of compressed oxygen or from automatic oxygen generators. When in use the inlet nipple D of the carbureter is connected by tubing to the oxygen supply and as soon as the valve on the oxygen apparatus is opened gas flows into the pipe E to the coil E', the condensation chamber C and the coil H to the valve head J, from which it may be admitted by the needle valve L to the pipe K leading to the bottom of the upper compartment B which has previously been filled with the liquid to the level of the outlet plug a. Upon passing up through the absorbent material to the outlet cock Q the oxygen or air becomes carbureted or saturated so as to burn readily at the orifice of a suitable burner, as for example, the tip of an ordinary calcium light jet. This burner should be of a type adapted to burn such mixture of inflammable gas and a supporter of combustion such as oxy-

gen or atmospheric air. The outlet hose nipple O of the needle valve N for the uncarbureted oxygen is connected to the inlet of the burner which is adapted to receive 5 the gas which is the supporter of combustion, consequently the carbureted gas issuing from outlet X and the uncarbureted oxygen issuing from the nipple O can be proportioned at the burner as desired.

- 10 In the manipulation of the apparatus the needle valve N is kept closed and the inflammable vapor is first ignited, its flow being controlled by the needle valve L. When the vapor is burning properly the needle valve 15 N is opened, which permits pure air or pure oxygen to arrive at the burner and there mix with the carbureted gas in sufficient proportion to cause practically complete combustion, so that the flame is of the highest temperature 20 attainable considering the calorific value of the liquid used and its volatility.

This type of carbureter is adapted to be used in connection with burners consuming two gases or in connection with a burner 25 adapted to consume a single gas after it has become carbureted with the vapor of the liquid used. When used in connection with automatic oxygen generators which generate gas from the reaction between compounds 30 such as peroxid of sodium and water, there is a certain amount of water vapor carried from the generator which would ordinarily tend to collect in the chamber containing the absorbent material. In the carbureter here- 35 in described this vapor of water or other liquid, which may contaminate the supply of oxygen or air, condenses in the coils E' and H and is deposited in the condensation chamber C. This action is stimulated by the cold 40 produced by the rapid vaporization of the liquid which in practice causes a very marked drop in temperature within the carbureter.

If at any time it becomes desirable to 45 change the absorbent material or filling of the carbureter, the cover R may be removed, which exposes an opening sufficiently large for that purpose. For the purpose of filling the carbureter with liquid it is only necessary 50 to remove the hollow plug W, which is provided at its upper portion with a hexagon e.

It is obvious that many forms of this invention may be embodied without using the 55 exact construction shown.

I claim and desire to obtain by Letters Patent the following:

1. A carbureter comprising a carbureting chamber, a condensation chamber separated 60 therefrom, a pipe for gas to be carbureted leading tortuously through the carbureting

chamber to the condensation chamber, a pipe leading from the condensation chamber and having two branches, one branch delivering outside the carbureter and having a controlling valve for educting gas uncarbureted, and the other branch opening into the carbureting chamber below the normal liquid level therein, and a valve for controlling the last said branch. 65

2. A carbureter comprising a carbureting chamber, a condensation chamber separated therefrom, a pipe for gas to be carbureted leading through the carbureting chamber to the condensation chamber, a pipe leading 70 from the condensation chamber within the carbureting chamber and having two branches, one branch leading outside the carbureter and provided with a valve for educting gas uncarbureted and the other opening 75 into the carbureting chamber below the normal liquid level therein.

3. A carbureter comprising a carbureting chamber, a coil therein connected to receive gas to be carbureted and in which the gas is 80 cooled, a condensation chamber to which the said coil delivers, and a pipe for conducting the gas from the condensation chamber back into the carbureting chamber and delivering it near the bottom thereof, and a valve 85 for controlling the flow of such gas.

4. A carbureter comprising a carbureting chamber, a coil therein connected to receive gas to be carbureted and in which the gas is 90 cooled, a condensation chamber to which the said coil delivers, and a branch pipe and valve for leading off some of the gas after cooling and condensation and without carbureting.

5. A carbureter of the class described, comprising a chamber having carbureting and condensation compartments, absorbent material placed within said carbureting compartment, a condensation coil within the carbureting compartment and in communication with the condensation compartment, means for conducting the flow of gas from condensation compartment to the bottom of said carbureting compartment, a valve controlling and regulating said flow of gas to 100 the bottom of carbureting compartment and a secondary connection and valve for controlling the flow of the uncarbureted gas or other supporter of combustion. 105

In testimony whereof I have signed this 110 specification in the presence of two subscribing witnesses.

NELSON GOODYEAR.
